UNITED STATES PATENT OFFICE.

WILLIAM A. ARNOLD, OF LOWELL, MASSACHUSETTS.

DESIGN FOR A MONUMENT.

52,015.

Specification for Design.

Patented May 7, 1918.

Application filed April 19, 1917. Serial No. 163,296. Term of patent 14 years.

To all whom it may concern:

Be it known that I, WILLIAM A. ARNOLD, a citizen of the United States, residing at Lowell, in the county of Middlesex and Commonwealth of Massachusetts, have invented a certain new, original, and ornamental Design for Monuments, of which the following is a specification, reference being had to the accompanying drawing, forming a part thereof.

The figure is a perspective view of a monument, showing my new design.

What I claim as new and desire to secure by Letters Patent, is—

The design for a monument as shown.

In testimony whereof I have signed my name to this specification in the presence of two subscribing witnesses.

WILLIAM A. ARNOLD.

Witnesses:

ALBERT M. MOORE,
DENNIS J. MURPHY.
